LOUIS HIRSCH, OF EVERGREEN, NEW YORK.

ART OF MAKING HOSIERY.

1,052,723.

Specification of Letters Patent. Patented Feb. 11, 1913.

Application filed April 3, 1911. Serial No. 618,515.

To all whom it may concern:

Be it known that I, LOUIS HIRSCH, a subject of the King of Saxony, but now residing at Evergreen, in the county of Queens 5 and State of New York, have invented certain new and useful Improvements in the Art of Making Hosiery, of which the following is a specification.

My invention relates to the art of fabricating the welt of a stocking.

The general object of my invention is to provide a novel mode for uniting a stocking welt with a stocking leg so as to effectually guard against raveling of fabric when a 15 ladder or run starting in the welt and of its extending beyond the same.

Hitherto as the welts of stockings have been fabricated on a knitting machine as a part of the leg, when garters were applied 20 thereto, owing to undue strain upon the threads of the fabric thereof, they constantly have been found to part or ravel which not only affected the welt but also impaired the leg of the stocking to such an 25 extent, as practically to render the same useless.

Hence, the principal object of my present invention is to avoid the above defined objectionable feature constantly occurring in 30 the use of hosiery, and to provide a stocking having a welt in which if raveling occurs will be confined to the welt of the stocking alone.

The nature and scope of my present invention will be more fully understood from 35 the following description taken in connection with the accompanying drawings, showing several well defined methods for the knitting and completing of the welt as part 40 of the leg of a stocking, in which—

Figure 1, is a plan view of sinker formed loops interlaced with needle formed loops and a hook-frame to manually hold the first course of sinker loops away from the needles 45 during regular knitting of the welt and also other manipulations of the said hook-frame. Fig. 2, is a side elevational view, in detail of the sinker formed loops of Fig. 1, held together out of action of the needles 50 on the hook-frame and also showing a needle formed loop held on the needle-shank. Fig. 3, is a view in perspective, diagrammatically of a series of bearded needles with loops on the needle-shanks out of 55 range of the beards of said needles and also the loops formed on the same needles, but

transferred to other needles of the series of the bed by means of yarn or by action of needles alone, to provide a certain interlacing where the welt joins the leg of the 60 stocking. Fig. 4, is a sectional elevational view of elements employed in a flat bar knitting machine to effect the method of Figs. 5 and 6, one of the bearded needles with yarn in connection therewith being 65 shown, and also loops held on the shank of the needle so that when two sinker loops are caught under the beard of the needle with a new yarn the loop on the needle-shank will be cast over the three loops to become interlaced. Fig. 5, is an elevational view, in detail of the completed result, of 70 Fig. 4, showing the welt and character of interlacing of the yarn where the welt joins the leg; and Fig. 6, is an enlarged view of 75 three sinker loops interlaced with yarn by needles according to the method of Fig. 4.

Referring to the drawings *a*, is one of a series of needles having beards *a*¹.

*a*², is yarn manipulated by the needles. 80

b, is a movable sinker having a nose *b*¹.

c, is a presser-bar underneath the sinker *b*.

d, is a knocking off bit arranged below the presser-bar and adapted to be acted upon to hold a loop formed by a sinker on the 85 needle-bar away from a loop formed by a needle on the needle-bar, either above or below the nose of a sinker *b*.

In Fig. 3, a mode is illustrated of transferring sinker loops *f*, onto needles located 90 two or more spaces away from the needles between which these loops were formed, the purpose of which is to enable thereby a staggered interlocking of the yarn and loops where the welt forms the leg of the stocking, thereby effectually preventing in the event of raveling of the welt it extending into the leg to thus impair the usefulness 95 of the stocking.

In Figs. 1, 2, 4, 5 and 6, is illustrated a 100 mode of providing an additional interlacing of loops manually by drawing off the first course of sinker-loops *f*, onto a hook-frame *e*. Continuing then plain knitting for two courses, and when the third course of sinker 105 loops *f*², are formed, placing the same over the first course of loops *f*, of the hook-frame *e*, and again continuing plain knitting until the welt is completed. The two sinker formed loops *f* and *f*², held by the hook-frame *e*, are then placed over the bearded needles *a*, and loops *f* and *f*², of the yarn *a*², 110

are caught under the beards of the said needles *a*, and passed through the needle loops *f*¹, and then cast off to complete the interlaced looping as illustrated in Fig. 5, 5 where the completed welt 10, joins the leg of the stocking 12. The character of interlacing of the loops at such point is clearly shown at 14, in Figs. 2 and 5.

It will be seen from the foregoing description that sinker loops held by the needle-bars out of action of the needles *a*, are not replaced on the same needles in which they were formed, but preferably certain adjoining needles of the course of needles, 15 for example, as indicated in dotted outline in Fig. 3, to provide a staggered relationship of the sinker and needle loops in their interlacing.

Having thus described the nature and objects of my invention, what I claim as new 20 and desire to secure by Letters Patent is:—

1. The method of forming a welt on a flat bar knitting machine, which consists in manually drawing off the first course of 25 sinker loops, in then continuing plain knitting for two courses, in then knitting a third course of sinker loops and placing over the first course of loops, in then knit-

ting plain fabric until the welt is completed, the two sinker formed loops held, as described, being placed over the bearded needles and the loops of yarn caught under the beards of said needles and passed then through said needle loops, and in then casting off to complete the interlaced looping 30 where the completed welt unites with the leg of the stocking. 35

2. The method of forming a welt on a flat bar knitting machine, which consists in transferring sinker loops onto needles located two or more spaces away from the needles between which the said loops were formed in knitting fabric, in then returning to needles in action the said sinker formed loops and drawing such loops then through the last knit course of the fabric, and in then knitting further courses through the 40 said loops for the formation of the body of the fabricated article. 45

In witness whereof, I have hereunto set 50 my signature in the presence of two subscribing witnesses.

LOUIS HIRSCH.
